United States Patent Office

Des. 184,608
Patented Mar. 17, 1959

184,608

SIDEBURN GAUGE OR SIMILAR ARTICLE

Dominic J. De Fano, River Grove, and Robert Irwin Kallman, Geneva, Ill., assignors to Jacob Cohen, Chicago, Ill.

Application February 19, 1958, Serial No. 49,701

Term of patent 14 years

(Cl. D52—1)

FIG. 1

FIG. 2

Figure 1 is a perspective view of a sideburn gauge, showing our new design; and

Figure 2 is an enlarged fragmentary cross-sectional view taken substantially on the line II—II of Figure 1 looking in the direction indicated by the arrows.

The side not shown is substantially like the side shown.

We claim:

The ornamental design for a sideburn gauge or similar article, substantially as shown and described.
